FURNACE TILT LIFT DOOR AND SEAL

Levi S. Longenecker, Mount Lebanon, Pa.

Application January 21, 1949, Serial No. 71,907

8 Claims. (Cl. 110—173)

1

This invention relates to furnace structures of the all-door front wall type and more particularly to tilt lift doors for such furnaces and seals for closing the clearance gaps between such doors and between the end doors and the door jambs.

Patent 2,045,662 issued to me on June 30, 1936, discloses a furnace of the all-door front wall type having tilt lift doors equipped with seals for closing such clearance gaps. Each of these seals comprises a frame having a long leg which bears against the off furnace side of two adjacent doors and overlaps the clearance gap therebetween, and a short leg which projects toward the furnace and lies on top of such doors in overlapping relation to the top of such gap.

This short leg which lies on top of such doors is carried by that door of the pair which is raised ahead of the other, or by both such doors when they are raised at the same time and speed.

A furnace having an all-door front wall, having tilt lift doors and seals of the type described above is also disclosed in an application Serial No. 659,014 filed by me on April 2, 1946, which application has now matured as Patent No. 2,494,713, dated January 17, 1950.

These prior seals are counterweighted in an attempt to keep them from falling in the event they become dislodged from the tops of the doors during operation, and while they have been effective in closing the clearance gaps, they have given much trouble and have been a more or less constant source of danger. Counterweighting the seals is not the solution of the problem, and an object of this invention is to produce an improved and safe door and seal construction for tilt lift doors of the all-door front wall type of furnace.

Another object is to produce an improved seal for closing the clearance gap between adjacent doors and between the end doors and the door jambs of an all-door front wall type of furnace equipped with tilt lift doors.

A further object is to produce improved sealing means for the clearance gaps between vertically movable furnace doors of the tilt lift type.

A still further object is to produce sealing means for the clearance gap between two adjacent vertically movable furnace doors of the tilt lift type and an improved door for co-operating with such sealing means in the sealing of such gap whereby such sealing means can be carried by and secured to one such door in such manner as to adjust itself when one such door

2

is tilted and lifted independently of the other door.

Another object is to produce an improved refractory lined sealing means for closing the vertically extending gap between adjacent vertically movable furnace doors.

These and other objects I attain by means of the structures described in the specification and illustrated in the drawings accompanying and forming part of this application.

In the drawings:

Figure 1 is a more or less diagrammatic view in side elevation of two furnace doors of the tilt lift type equipped with a seal closing the clearance gap therebetween. One such door is shown in closed position and the other in partially open or raised position;

Fig. 2 is a view similar to Fig. 1, but in which both doors are closed;

Fig. 3 is a more or less diagrammatic view in front elevation of an all-door front wall furnace structure equipped with three tilt lift doors and four seals embodying this invention. In this view, one door is shown closed and the other two partially raised;

Fig. 4 is a view in front elevation of a furnace door and two seals carried thereby embodying this invention;

Fig. 5 is a top plan view of the door and seals of Fig. 4;

Fig. 6 is a sectional view taken on line VI—VI of Fig. 4;

Fig. 7 is an enlarged detail view of the upper part of the two doors and seal of Fig. 1;

Fig. 8 is an enlarged fragmentary view showing a portion of the upper parts of the door and seal structures of this invention;

Fig. 9 is a top plan view of those parts of the two door and seal portions shown in Fig. 7;

Fig. 10 is a view taken on line X—X of Fig. 8;

Fig. 11 is a top plan view of the seal for the clearance gap between the tops of two adjacent doors of the tilt lift type embodying this invention;

Fig. 12 is a view in side elevation of the seal member shown in Fig. 11;

Fig. 13 is a sectional view taken on line XIII—XIII of Fig. 11;

Fig. 14 is a sectional view taken on line XIV—XVI of Fig. 11;

Fig. 15 is a perspective view of one of the regular blocks or tiles used to line the cast shell of the seal of this invention;

Fig. 16 is a perspective view of one of the special blocks or tiles used in making the seal lining;

Fig. 17 is a sectional view taken on line XVII—XVII of Fig. 20;

Fig. 18 is a sectional view taken on line XVIII—XVIII of Fig. 17;

Fig. 19 is a sectional view taken on line XIX—XIX of Fig. 20; and

Fig. 20 is a fragmentary view in elevation looking at the furnace side of the seal.

The furnace chosen for the purpose of illustrating this invention is disclosed in Figure 3 and comprises an all-door front wall structure having a charging opening which extends from sill 25 to the bottom of lintel 26 and from the inner face of jamb 27 to the inner face of jamb 28. This opening is controlled by three tilt lift doors *a*, *b* and *c* which are adapted to be manipulated by mechanisms such as disclosed in my said Patent No. 2,494,713. Each of the doors *a*, *b* and *c*, extending along each of its vertical edges on its off furnace side, is provided with an angle member 29 and each of the jambs 27 and 28 is provided with a similar angle member. These angle members are arranged on opposite sides of each of the clearance gaps 30 existing between adjacent doors and between the end doors *a* and *c* and jambs 27 and 28 to form channels for the seals which as an entirety are numbered 31.

Each of the doors *a* and *c* is provided with two seals which are adapted to close the four clearance gaps; two between the center door *b* and doors *a* and *c* and two between end doors *a* and *c* and jambs 27 and 28.

Each seal 31 comprises a channel-shaped cast steel shell having flat parallel side walls 32—32 provided with inwardly projecting pairs of sectional key ribs or flanges 33 which extend upwardly from horizontally extending cross members 34.

Keyed in place by key members 33—33 and supported on cross members 34 are interlocking refractory blocks or tiles 35 and 35a (Figs. 15 and 16) which are provided with side slots 36 which co-operate with keys 33 to lock each block into the seal shell.

Each cross bar 34 carries three blocks or tiles; the two lower ones being regular tiles 35 and the upper one being a special tile 35a. These special tiles are either specially formed or are regular tiles that have portions broken away to decrease the height of the inner corner portions of the body behind grooves 36 as shown in Fig. 16 to permit them to be inserted in place in front of cross members 34 (see Fig. 18).

Interlocking of the individual blocks or tiles is accomplished by means of the interfitting triangular tongues 37 with the triangular grooves 38. Such interlocking is broadly disclosed in a number of patents issued to me such as Patents Nos. 2,387,594; 2,240,190; 2,126,901; 2,045,661; 2,024,649 and 1,874,321.

The outer face of each block or tile terminates in the same plane as the outer edges of the side walls 32—32 of the seal casting.

Each of the furnace doors *a*, *b* and *c* comprises a main one-piece steel casting of corrugated design substantially as disclosed in Patent 2,387,594 issued to me on October 23, 1945. Each of these doors is preferably operated and controlled by hoisting means and counterweights such as disclosed in my said Patent No. 2,494,713. Each door, instead of having seal supporting means adjacent each end of the top of the door as in said application and in said Patent 2,387,594, is provided with a depression 39 at each such end; each such depression having a circular bot-

tom which is straight across from side to side so as to receive and co-operate with the cylindrical surface of a sealing roller 40.

Sealing roller 40, the detailed construction of which is disclosed in Figs. 11 to 14 inclusive and will be later described, is mounted for rotation on a bearing pin 41 which projects laterally from one end and is preferably formed as a unitary part of a support arm 42 having adjacent its opposite end a cylindrical cross member 43 which parallels such bearing pin.

Cross member 43 at its distal end has a reduced end portion 44 and bearing pin 41 at its distal end has a reduced portion 45. Reduced portions 44 and 45 snugly fit within circular holes drilled for their reception in a support arm 46 which parallels support arm 42 and is held in operative relation thereto by means of a bolt 47 which extends through a tubular spacer member 48 which surrounds such bolt and is positioned between support arms 42 and 46.

Side members or walls 32 of the seal castings have ears 49 which extend upwardly above the tops of the doors when such doors are in closed position and the seals are in clearance gap sealing position. Ears 49 are slotted as at 49a (Fig. 8) to loosely receive cylindrical cross member 43 which serves as the pivot pin for the sealing roller assembly shown in Figure 11.

A member 50 connects ears 49 and extends above the tops of the same (Fig. 8) and serves to limit tilting of the roller assembly away from the furnace so that its center of mass when the seal is in vertical position is always on the furnace side of the pivotal point of the roller assembly. This arrangement makes certain that the sealing roller is always in sealing position when the doors defining the gap to be sealed are closed.

Each seal 31 is suspended from its door or its door jamb, as the case may be, by a flexible support which permits tilting movement of such seal with relation to the door or door jamb to which it is secured. This tilting movement is limited by flexible means secured to the seal adjacent its upper end and to the door or jamb at a point adjacent its top. The flexible support for each seal preferably comprises a chain 51 having its upper end secured by means of an adjustment bolt 52 to a bracket 53 secured to the door or the door jamb. Each bolt 52 is provided with an adjusting nut and a lock nut which together are numbered 54 (Fig. 4). The lower end of each chain 51 is secured to a bracket 55 which is bolted as at 56 to a pad 57 formed on the cast shell of the seal. Each chain 51 thus forms a floating support for seal 31. Tilting movement of each seal relative to the door or jamb to which it is secured is limited by a chain 58 having one end secured to the top of the door as at 59 and the other end secured to an angle member 60 as at 61. Angle member 60 and a plate member 60a which closes slots 49a are bolted as at 62 to cross member 50 which connects ears 49 and is provided with an arm 63 which extends partially around a member 64 secured to and extending upwardly above the door top. Arm 63 limits movement of the seal laterally away from the door when the off-door side of the seal is unconfined as when the door carrying the seal is raised above the adjacent door or door jamb as the case may be.

The door jambs 27 and 28 have the same inclination to the vertical as the doors when in closed position resting against the furnace lintel.

The chains permit independent tilting of the doors to and from vertical position.

The seals for closing the clearance gaps between doors *a* and *c* and the jambs can, if desired, be secured to the jambs instead of to doors *a* and *c*, and the seals for the clearance gaps between doors *a* and *b* or *b* and *c* can be carried by door *b* or one can be carried by door *b* and the other by door *c* or door *a*, as desired. In fact, the possibility of a number of different arrangements of seals for closing the gaps will be apparent.

If the seals for closing the gaps between doors *a* and *c* and the jamb are carried by the jambs, the door ends of the chains will be secured to the jambs instead of the door and a member corresponding to member 64 will be secured to the top of each jamb to cooperate with member 63.

With the arrangement of doors and seals disclosed in Figure 3, the sealing rollers 49 of the seals attached to door *c* are resting within depressions 39 of door *c*; doors *b* and *c* being in vertical position having been righted before being raised to the position shown. Door *a* which is closed, is resting in inclined position against the furnace and roller seal 49 for closing the top of the clearance gap between doors *a* and *b* has been swung up by door *b* and is riding on the channel member 29 attached to and forming part of door *b*; seal 31 for the clearance gap between doors *a* and *b* having been moved to vertical position by door *b*.

What I claim is:

1. The combination with two vertically movable furnace doors arranged side by side and which when closed are supported in inclined position against the furnace and must be righted before being raised, of a seal for closing the clearance gap between such doors and which comprises a member adapted to lie against the off furnace side of such doors and overlap such gap when the doors are closed, an agent hinged to the upper part of such member and which when such doors are closed is adapted to lie on top of such door in overlapping relation to the gap between the door tops, and means anchoring such member to one such door whereby such member and such agent are carried by such door as the same is raised and lowered.

2. A structure as defined in claim 1 in which that part of the agent which is arranged in overlapping relation to the gap between the tops of such doors comprises a roller having a horizontal axis which parallels the plane of the furnace face of the doors.

3. A structure as defined in claim 1 in which the means anchoring the member to one of the doors is flexible and is so arranged as to permit relative tilting movement between such member and the door to which such member is anchored.

4. A structure as defined in claim 3 in combination with flexible means for limiting such tilting movement.

5. A structure as defined in claim 1 in which that part of such agent which is arranged in overlapping relation to the gap between the tops of such doors comprises a roller, and in which the top of each door is provided with a curved seat for receiving such roller.

6. The combination with a vertically movable furnace door which when closed is supported in inclined position against the furnace and must be righted before being raised, of a door jamb at one end of the opening controlled by such door and having the same inclination to the vertical as said door when said door is in closed position, a seal for closing the clearance gap between such door and jamb and which comprises a member adapted to lie against the off furnace side of both such door and jamb and overlap such gap when such door is closed, an agent hinged to the upper part of such member and which when such door is closed is adapted to lie on the top of such door and such jamb in overlapping relation to the top of such gap, and means anchoring such member to such jamb and being constructed and arranged to permit tilting of such member with relation to such jamb when such door is raised.

7. A structure as defined in claim 6, in which the means for anchoring the member to the jamb comprises flexible members which are so arranged to permit relative tilting movement between the member and such jamb.

8. A structure as defined in claim 6, in which said agent comprises a roller and in which the top of the jamb and the top of the door are each provided with a curved seat for receiving such roller.

LEVI S. LONGENECKER.
